UNITED STATES PATENT OFFICE.

RICHARDSON ROWNTREE, OF SEATTLE, WASHINGTON.

BARREL, KEG, OR THE LIKE.

1,309,779.

Specification of Letters Patent. Patented July 15, 1919.

Application filed February 13, 1918. Serial No. 216,888.

To all whom it may concern:

Be it known that I, RICHARDSON ROWNTREE, a citizen of the United States, residing at Seattle, county of King, State of Washington, have made a certain new and useful Invention in Barrels, Kegs, or the like, of which the following is a specification.

This invention relates to barrels, kegs, tubs, hogsheads, or the like, and which I will hereinafter generically refer to as receptacles.

The object of the invention is to provide a light, strong, durable, and cheap receptacle of the character described.

15 A further object of the invention is to provide a veneered receptacle of the character described.

A further object of the invention is to provide a veneered receptacle which is exceedingly light in weight, and which is made up of but few standard parts which may be readily assembled together, and which, due to the unique method of joining the respective parts together, is exceedingly strong.

25 Further objects of the invention will appear more fully hereinafter.

The invention consists substantially in the construction, combination, location, and relative arrangement of parts, all as will be more fully hereinafter set forth, as shown by the accompanying drawings, and finally pointed out in the appended claims.

Referring to the drawings:

Figure 1 is a view in elevation of a receptacle constructed in accordance with my invention.

Fig. 2 is a plan view of the same.

Fig. 3 is an enlarged plan view of a section of the receptacle showing a butt joint.

40 Fig. 4 is a view in side elevation of one form of rim joint.

Fig. 5 is a similar view showing lap joints of the stave.

Fig. 6 is a sectional view through the end 45 rim of the receptacle.

Fig. 7 is a similar view of a modified rim section.

Fig. 8 is a horizontal sectional view showing one form of stave joint.

50 Figs. 9, 9^a, 9^b, 9^c, 9^d and 9^e show a number

of stave joints in section which may be employed in accordance with my invention.

Figs. 10, 10^a, 10^b and 10^c are similar views showing a number of lap joints or joints between end rims and staves.

55

Figs. 11, 11^a and 11^b show a number of modified types of joints and end rims in section.

Figs. 12, 12^a and 12^b show in section a number of modified forms of groove joints 60 between the heads and the rims that may be employed in accordance with my invention.

Figs. 13, 13^a, 13^b and 13^c show in plan various modified forms of joints that may be 65 employed between rim sections.

The same part is designated by the same reference character wherever it occurs throughout the several views.

It is a well established fact in the art that 70 hard wood barrels, kegs, hogsheads, or more generally, receptacles, of this nature, are preferable to soft wood receptacles of this nature due to the strength thereof, and the lightness thereof. For a given or required 75

strength a hard wood receptacle is many times lighter than a soft wood receptacle of the same strength. Due, however, to the fact that hard wood is constantly increasing in price and is growing scarcer every year it is 80

hard to obtain the same for ordinary use. It is among the special purposes of my present invention to provide a veneered barrel with a hard wood veneer which has all of 85

the advantages that a hard wood barrel or receptacle has over the soft wood receptacle, and which in addition has marked advantages over the solid hard wood receptacle. In the first instance I am enabled to make a large saving in the hard wood material. I 90

am secondly enabled to decrease the weight of the receptacle for a given strength from forty to fifty per cent. thereby facilitating handling and enabling an economical shipment of receptacles of my construction by 95

freight or express. Weighing less, it is obvious that the receptacle is cheaper to handle. Being veneered the receptacle is stronger and less liable to crack than is the solid wood receptacle even though it is con- 100

structed of one-half the thickness of the solid wood receptacle.

Veneered woods are now made in three 5 ply and five ply wood or thicknesses; sometimes of all soft woods, sometimes of all hard woods, and sometimes of mixed woods, and while I have shown and will now describe my invention as applied to a three 10 ply wood with a soft wood body and a hard wood inner and outer veneer, I wish it to be understood that my invention in its broadest scope is not to be limited thereto, but is to be construed in the broadest interpretation of the foregoing definition. Likewise 15 while I have shown and will now describe my invention as embodied in a veneered barrel, I wish it to be understood that I do not desire to be limited or restricted thereto, as the invention can be readily applied to receptacles of any nature. In the form of 20 my invention shown in the drawings I propose to construct the receptacle, and in this instance the barrel, indicated generally at 1, of four staves, each stave being previously 25 veneered. I provide each veneered stave with solid edges and ends, and join the edges and ends together by joints or connections of any suitable or desired nature, but preferably of such construction 30 that at no place of joinder between the various elements of the barrel structure is there a straight line of connection which might tend to render the joint weak or separable. The four staves I have shown at 35 2, 3, 4 and 5, are each provided with an inner veneer 6 and an outer veneer 7. To the edges of the veneered staves are secured, in any suitable means and preferably by glue, a solid piece of wood indicated at 8. These 40 pieces of wood 8 form the meeting or adjoining edges of the staves 2, 3, 4, and 5. Each stave has also a solid piece of wood indicated at 9 glued to each end of the stave to form the rim at the top and bottom. One of the essential requirements for 45 the manufacture of veneered receptacles of this nature is that the barrel or receptacle can be assembled when the three pieces of wood which constitute each stave, namely, 50 the stave, edge, and rim portions, are glued together to form the veneered board, the glue is pressed out at all edges, and when the board is dry, for all work of this nature is done under heat, the edges are 55 trimmed off. As it is necessary for each stave to have solid edges and ends because without them the edges of the veneered material would come apart in handling the barrel and as the barrel would be of short life 60 and would be quickly knocked to pieces, the parts mentioned must be glued together to form the complete stave before the stave is veneered, cooled, dried and trimmed, therefore the seven pieces which constitute the

complete stave are all cut and bent, then 65 glued together in one operation, the seven pieces referred to being the core 5, the two veneers 6 and 7, and the two end rims 9, one at each end of the barrel. These parts are all glued together in one operation under 70 pressure, and consequently no trimming is required. The respective pieces of wood 8 at the edges of each stave may be joined together in any suitable manner, and while I have shown in Fig. 9 various types of 75 joints that may be employed for this purpose, I do not desire to be limited or restricted to any particular type or form of joint. Likewise the lap joint between the pieces of wood 8 and the body 5 of the stave 80 may be strengthened in any suitable or desired manner. For example, in Fig. 10, at 12 I show a continuous tongue and groove, and at 13 a butt joint; at 14 a spline joint, and at 15 a doweled joint. The rims 9 may 85 be strengthened in their joinder with the staves 2, 3, 4 or 5, as the case may be, by any suitable form of joint, preferably one of the various joints shown in Fig. 10. The rims 9 are constructed to permit the head 90 16 at the top and bottom of the barrel to be retained therein. The head 16 may likewise be veneered, that is, with a body and two veneered surfaces as shown in Figs. 6, 7, and 12, although I do not desire to be limited in this respect as any type of head may be employed. In Fig. 12 I show three types of head and rim joiner, the first being a flat edged head countersunk in the rim; the second being a rounded edged head countersunk in the rim; and the third being a head 100 flush with the inner edge of the rim with a spline joint between the two. In Fig. 6 I show an angular head countersunk in a coöperating angular seat in the surface of 105 the rim. In Fig. 7 I show the head 16 seated on a jog on the inner surface of the rim 9 and flush with the surface thereof held in place by a band 20 which may be suitably secured to the rim 9 by nails, screws, 110 or the like, as indicated. The rim sections 9 of each stave may be secured to each other in any suitable or desired manner, and in Fig. 13 I show various types of joints for 115 this purpose, 21 being a horizontal lap joint, 22 a vertical lap joint, either or both of which may include in connection therewith a pin, the holes for which are indicated at 23. At 24 and 25 I show either horizontal or vertical tongue and groove joint or dove-tailed joint respectively. Likewise in Figs. 4 and 5 a still further modified joint for the end rim is shown. From the foregoing it is apparent that with any one of the joints employed there is not a straight line through 120 any piece of the barrel or where two pieces meet together, and as above explained many other types of joints will readily occur to 125

those skilled in the art for this purpose without departing from the spirit or scope of my invention as defined in the claims.

In connection with the foregoing hoops or bands indicated at 29 may be employed. On standard barrels there are now employed eight hoops, two at each end only a fraction of an inch apart, but in accordance with my invention I employ merely two end hoops in one piece of substantial width as shown. Wide end hoops of this nature greatly increase the strength of the barrel and also the glued end rim joints, so that it will take very great pressure to break the ends as will be readily understood.

Having now set forth the objects and nature of my invention, and having shown and described structures embodying the principles thereof, what I claim as new and useful, and of my own invention, and desire to secure by Letters Patent, is:—

1. A veneered barrel comprising a plurality of veneered staves joined together to form a smooth continuous contour without a straight transverse line of jointure therebetween.

2. A veneered barrel comprising a plurality of veneered staves, each consisting of a spaced inner and outer veneered strip with a body interposed therebetween, and each provided with solid pieces at the side and end edges thereof interposed between said spaced veneered strips and secured thereto with the outer side edges thereof flush with the outer surface of said strips, said side and end pieces being provided with means for engaging the side and end pieces of an adjacent stave without a straight transverse line of jointure therebetween.

3. A veneered barrel comprising a plurality of veneered staves, each consisting of a spaced inner and outer veneered strip with a body interposed therebetween, and each provided with solid pieces at the side and end edges thereof interposed between said space veneered strips and secured thereto with the outer side edges thereof flush with the outer surface of said strips, said side and end pieces being provided with means for engaging the side and end pieces of an adjacent stave without a straight transverse line of jointure therebetween, and said end pieces forming when assembled a barrel rim, and means for receiving a barrel head in said rim.

4. A veneered barrel comprising a plurality of veneered staves each provided with solid pieces secured to the side edges and ends thereof, and each of said side edge and end pieces provided with means to engage the side edge and end piece of an adjacent stave and to lie flush with the outer surface of said adjoining staves without a straight transverse line of jointure therebe-

tween, said end pieces forming, when assembled, a barrel rim, and means for receiving a barrel head in said barrel rim. 65

5. A veneered barrel comprising a plurality of staves each comprising a body and an inner and outer veneer and solid pieces secured to the side edges and ends thereof and lying flush with the outer surface of the outer veneer, and means for joining abutting edge and end pieces without a straight transverse line of jointure therebetween. 70 75

6. A veneered barrel comprising a plurality of staves, each comprising a body and an inner and outer veneer, and solid pieces secured to the side edges and ends thereof and lying flush with the outer surface of the outer veneer, and extending between the inner and outer veneer layers, and means for joining abutting edge and end pieces. 80

7. A veneered barrel comprising a plurality of staves, each comprising a body and an inner and outer veneer, and solid pieces secured to the side edges and ends thereof and lying flush with the outer surface of the outer veneer, and extending between the inner and outer veneer layers, and means for joining abutting edge and end pieces without a straight transverse line of jointure therebetween. 85 90

8. A veneered barrel comprising a plurality of staves, each comprising a body and an inner and outer veneer, and solid pieces secured to the side edges and ends thereof and lying flush with the outer surface of the outer veneer, and extending between the inner and outer veneer layers, and means for joining abutting edge and end pieces without a straight transverse line of jointure therebetween, said end pieces forming, when assembled, a barrel rim, and means for receiving a barrel head in said barrel rim. 95 100 105

9. A veneered barrel comprising four staves, each composed of a body and an inner and outer veneer, side edge pieces extending between the inner and outer veneer and glued to the body and formed to lie flush with the outer surface of the outer veneer, and provided with means for being secured to abutting edge pieces, end pieces extending between the inner and outer veneer and glued to the body, and likewise provided with means for being secured to abutting end pieces, said securing means comprising joints so constructed as to render the assembled structure without a straight transverse line of jointure between any two adjoining pieces. 110 115

10. A veneered barrel comprising four staves, each composed of a body and an inner and outer veneer, side edge pieces extending between the inner and outer veneer and glued to the body and formed to lie flush with the outer surface of the outer veneer, and provided with means for being secured

to abutting edge pieces, end pieces extending between the inner and outer veneer and glued to the body, and likewise provided with means for being secured to abutting 5 end pieces, said securing means comprising joints so constructed as to render the assembled structure without a straight transverse line of jointure between any two ad-

joining pieces, said end pieces, when assembled, comprising the rim of the barrel, and 10 means for securing a head to said end pieces.

In testimony whereof I have hereunto set my hand on this 21st day of January, A. D. 1918.

RICHARDSON ROWNTREE.
